UNITED STATES PATENT OFFICE.

HENRY G. ELFBORG, OF CHICAGO, ILLINOIS, ASSIGNOR TO AJAX RAIL ANCHOR COMPANY, OF CHICAGO, ILLINOIS, A CORPORATION OF DELAWARE.

RAIL-ANCHOR.

1,230,468.

Specification of Letters Patent. Patented June 19, 1917.

Application filed October 6, 1916. Serial No. 124,124.

To all whom it may concern:

Be it known that I, HENRY G. ELFBORG, a citizen of the United States, residing at Chicago, in the county of Cook and State of Illinois, have invented certain new and useful Improvements in Rail-Anchors, of which the following is a specification.

My invention relates to improvements in devices known as rail anchors or anti-creepers, which are employed for preventing the longitudinal creeping of railway rails on the ties; and the present invention is an improvement upon the devices described and claimed in my prior Patents, Nos. 1,083,603, dated January 6, 1914, 1,088,976, dated March 3, 1914, and 1,176,280, dated March 21, 1916.

In rail anchors of the kind most commonly used, a part of the structure abuts against a railway tie, and thus transmits to the tie the force exerted upon the rail by the rolling stock, thereby preventing the longitudinal movement of the rail with respect to the tie. The most convenient form of rail anchor is that in which the anchor consists preferably of two parts, having interlocking engagement along a plane inclined to the longitudinal axis of the rail, as described in my prior patents above referred to, whereby these parts when driven together are wedged tightly upon the rail, one of the parts being provided with a depending foot which abuts against a cross tie, so that in operation the depending foot prevents movement of the rail with respect to the tie, and at the same time the force acting longitudinally upon the rail tends to wedge the members of the anchor more firmly together, thereby increasing the frictional hold of the anchor upon the rail. In my prior patents, above mentioned, I have shown and described rail anchors of the type just referred to, in which the parts of the anchor are provided with two sets of inclined wedging surfaces, so that as one member of the anchor is moved relatively to the other longitudinally of the rail, the coacting wedging surfaces operate to effect a transverse gripping of the rail and also a vertical gripping, so that the rail is subjected to a double gripping action by the rail anchor. In my last mentioned prior Patent, No. 1,176,280, I have described and claimed an improvement in rail anchors, whereby the two parts of the anchor having

a coacting engagement with each other are prevented from being separated or disassembled by reason of the expansion of the rail or the movement of the traffic in the opposite direction to the creeping caused by the principal movement of traffic. As explained in my last mentioned prior patent, this separation of the parts of many rail anchors is caused by the expansion of the rail, or by the movement of the rail under the influence of the passing traffic in a direction adapted to move the rail anchor away from the coacting tie, instead of against it, so that unless the two parts of the anchor are held in fixed relation to each other, one part of the anchor is drawn away from the other, owing principally to the fact that the depending foot is embedded in the ballast of the roadbed, thereby lessening the gripping action of the rail anchor and destroying its efficiency as an anti-creeping device. This difficulty is increased in winter, when the ballast is frozen and embedded in snow and ice. The improvement in my last mentioned patent, whereby the separation of the members of the anchor is prevented, comprises co-acting parts on the two members of the anchor, in addition to the coacting surfaces by which the gripping of the rail is effected, so that as one member of the anchor is assembled on the other to effect the gripping of the rail, the coaction of the added locking surfaces will cause a locking engagement between the two parts of the anchor in order to prevent the separation thereof: more particularly this improvement of my prior patent comprises two locking surfaces, one of which inclines away from the other, so that the locking engagement increases as the rail-gripping action increases, but to a lesser degree, so that the action of the locking surfaces does not interfere with the rail-gripping action of the wedging surfaces.

The purpose of the present invention is to improve upon the devices of my prior patents briefly described above, by providing a rail anchor having inclined coacting wedging surfaces adapted to effect an increasing gripping action upon the rail as one member of the anchor is moved relatively to the other, and having also other coacting surfaces which engage each other with substantially constant pressure while the rail-gripping action effected by the in-

clined surfaces increases or decreases. These surfaces, coacting with constant pressure, serve to maintain the members of the anchor in adjusted position with respect to each other, regardless of the relative position of the coacting surfaces by which the rail-gripping action is effected, so that if the members of the anchor become slightly separated so as to decrease the rail-gripping action, the additional coacting surfaces, engaging each other with constant pressure, will prevent further separation of the members of the anchor, whereas relatively inclined surfaces would engage each other with decreasing pressure upon a slight separation of the members of the anchor, and thus permit a still further separation thereof. The provision of coacting surfaces engaging each other with substantially constant pressure is of importance for the further reason that it permits the two members of an anchor to be readjusted or re-assembled on a rail after the initial assemblage thereon, in a manner adapted to obtain the same degree of gripping action and the same locking effect as that obtained in the initial assemblage. A further feature of the present improvement is that as the rail-gripping action increases and the coacting inclined surfaces engage each other over an increasing area, the area over which the surfaces coact with constant pressure increases, so that when the parts of the anchor are assembled in operative position on a rail, these coacting surfaces will contact over a relatively large area. A further advantage of the rail and anchor embodying this improvement is that it may be applied to rails of varying size without affecting the rail-gripping action of the members of the anchor, and without affecting the action of the additional surfaces which coact with constant pressure to maintain the members of the anchor in assembled relation. The anchor is preferably so constructed that the surfaces which coact with substantially constant pressure are normally out of alignment prior to the assemblage of the members of the anchor, so that these additional coacting surfaces engage each other with a relatively high degree of pressure per unit of area, thus preventing separation of the anchor and maintaining the members of the anchor in rigid engagement with each other, so that they maintain a tight frictional engagement with the upper and lower surfaces of the rail base, in addition to the transverse gripping action which is imposed upon the rail base. These surfaces on the members of the anchor, which coact with substantially constant pressure per unit of area, may be used in connection with various forms of anchors having inclined wedging surfaces, and may be used in combination with the additional locking elements described and claimed in

my prior Patent No. 1,176,280 and illustrated in the present application.

The foregoing objects of my invention, and various other features and advantages, will appear more clearly from the following specification, taken in connection with the accompanying drawings, in which one embodiment of the invention is illustrated.

In the drawings

Figure 1 is a top plan view of a section of rail and a tie, showing my improved rail anchor assembled on the rail.

Fig. 2 is a vertical section through the rail of Fig. 1, showing my improved rail anchor in elevation.

Fig. 3 is a side elevation of a portion of a rail showing an end elevation of my improved rail anchor, looking toward the end of the main member upon which the wedge member is assembled.

Fig. 4 is a partial view similar to Fig. 3, showing an end elevation of the main or abutment member of the anchor and, by dotted lines, the wedge member at the instant when it is being passed into engagement with the main member.

Fig. 5 is a top plan view of the main or abutment member of the anchor in operative position with respect to a rail in which it is shown by dotted lines.

Fig. 6 is a view somewhat similar to Fig. 2, showing a side elevation of the main or abutment member with the wedge member removed therefrom.

Fig. 7 is a top plan view of the wedge member of the anchor.

Fig. 8 shows an end elevation of the wedge member by looking toward the right, as viewed in Fig. 3.

Fig. 9 is a perspective view of the wedge member shown in Figs. 7 and 8.

Fig. 10 shows an end elevation of the wedge member of the anchor looking toward the left, as viewed in Fig. 3; and

Fig. 11 shows an elevation of the wedge member, looking toward the left in Fig. 1.

Although my invention may be applied to rail anchors of various forms, I have preferred to illustrate it in connection with certain features of the rail anchors described and claimed in my prior patents above referred to, in which devices the members of the anchors are drawn together by the coaction of inclined wedging surfaces which transform relative longitudinal movement of the surfaces into a transverse rail-gripping movement of the members of the anchor. In the drawings, the main member A, which, for convenience, may be termed the reach bar or abutment member, is formed at one end with an upturned lip or jaw 1, in-turned at 2 to embrace the edge and part of the upper surface of the base of a rail 3. This member A extends beneath and in contact with the lower surface of the rail base,

and projects beyond the opposite edge of the rail base. At the end of the member A, opposite the jaw 1-2, there is an upstanding shoulder 4, the inner substantially vertical face 5 of which inclines toward the adjacent edge of the rail base in a direction toward the adjacent railway tie 7, by which the rail is supported. The member A is provided with a downwardly-extending abutment member 8, which is adapted to bear against the vertical face of the tie. The member A is also preferably provided with strengthening ribs 9. The smaller, or wedge member B of the anchor has in a general way the form of a box open along one side and at one end. From the upper wall of the opening or slot 17, along the side of the wedge member there depends a lip or wall 18, having along its inner face an inclined surface 5' corresponding in inclination to the inclined surface 5 upon the main member A. The wedge member is preferably closed at the end 19, but at the opposite end 20 the slot 17 is open, and the wedge member is recessed at 22 above the opening 17, forming the lip 23, which is adapted to overlie the edge of the rail base opposite that which is engaged by the jaw 1-2 of the main member. The lug 50 on the member A prevents tilting of the member B about an axis substantially parallel to the axis of the rail.

In assembling the device, the member A is placed under the rail with its lip or jaw 1-2 embracing one edge of the rail base, and with the abutment 8 bearing against one of the ties, the device being placed on that side of the tie from which the greatest volume of traffic moves. The member B is then mounted upon the member A by passing the open end of the member B over the wedge end of the member A, with the surface 5' coacting with the surface 5. As the relative movement of the members A and B continues, the coaction of the surfaces 5 and 5' will cause the members of the anchor to be drawn toward each other, and thus set up a transverse gripping on the edges of the rail base. This gripping action serves to hold the rail in a relatively fixed position with respect to the anchor, so that the abutment 8, bearing against the tie, will prevent a longitudinal movement of the rail on the ties under the influence of the passing traffic.

It will be seen that a slight relative movement of the members A and B of the anchor in a direction opposite to that adapted to effect the transverse gripping of the rail base will cause the members of the anchor to release in a slight degree their grip upon the rail base, and this lessening in the gripping action will cause the pressure between the coacting surfaces 5-5' to decrease, thereby permitting a still further separation of the

members of the anchor, and a still further decrease in the gripping action, until finally the members of the anchor may be entirely separated from each other, and will drop off the rail. This action of the members of the anchor, by which they become disassembled, has a tendency to occur by reason of the passage of the traffic in a direction opposite to that in which the rail normally tends to creep, or because of the expansion of the rail due to changes in temperature. I have provided improved means for overcoming the objectionable tendency just referred to, by providing the members of the anchor with other coacting surfaces which are adapted to engage each other with substantially constant pressure, regardless of the relative position of said members so that the separation thereof is prevented, and a total separation thereof is made impossible, even if the members of the anchor separate to a sufficient degree to decrease the gripping action on the rail. For this purpose the underside of the end of the reach bar A, opposite the jaw 1-2, is provided with a surface 10, which lies in a horizontal plane parallel to the lower surface of the rail and parallel to the longitudinal axis of the rail. The opening or slot 17, along the side of the wedge member B has its lower face 10' arranged to lie in a horizontal plane when the member B is assembled on the member A, and this surface 10' is adapted to coact with the surface 10 of the main member. The parts of the anchor are so constructed that the surface 10' is normally out of alignment and interferes with the surface 10 when the members are first brought into engagement with each other, as shown in Fig. 4, with the lip 23 engaging the upper surface of the rail base, and with the member A coacting with the lower surface thereof. In order to permit and facilitate the assemblage of the members A and B, the end of the surface 10' at the open end 20 of the wedge member is provided with a fillet or curved part 10^a which is adapted to engage a corresponding fillet or curved part 10^b at the end of the surface 10 on the main member, these curved parts being adapted to engage each other when the wedge member is first passed into contact with the main member, as illustrated in Fig. 4, and then, upon driving the wedge member toward the tie, these fillets will permit the initial movement of the wedge member, which may stretch slightly owing to the elasticity of the material from which it is constructed, thus permitting the wedge member to pass completely over the end of the main member to a rail-gripping position, and effecting a substantially constant pressure of relatively high degree between the coacting surfaces 10 and 10' as the rail-gripping movement takes place. As the member B is driven on to the member A the lip 23

will engage the rail base with a relatively high degree of pressure, owing to the interference of the horizontal surfaces 10—10', and thus maintain the member A in close contact with the under surface of the rail. Inasmuch as the surfaces 10 and 10' engage each other with substantially constant pressure, it will be seen that the coaction of these surfaces will not set up an increasing resistance to the rail-gripping movement of the member B, but will permit said member to be driven toward the tie until the coacting surfaces 5—5' cause an effective transverse gripping of the rail. As this rail-gripping movement continues, the area of contact of the surfaces 10 and 10' will increase, and thus when the parts of the anchor are assembled in operative position on a rail, the surfaces 10 and 10' will be in contact over a relatively large area, as shown, but in any position of the member B with respect to the member A the surface 10 will engage the surface 10' with a relatively high degree of pressure, thereby preventing the accidental separation of the members of the anchor, or the separation thereof due to the influence of the traffic in a direction opposite to that in which the rail tends to creep under the influence of the normal traffic, and at the same time these coacting surfaces, engaging each other with constant pressure, will prevent a tilting of the wedge member away from the rail, and will maintain the lip 23 in tight contact with the upper surface of the rail base.

In connection with the foregoing construction, I may provide locking means, such as shown and described in my prior Patent No. 1,176,280, this locking means comprising a depending lug 50 from the underside of the main member or reach bar A, adapted to contact with the surface 51 below the opening 17 in the member B. These coacting parts 50 and 51 serve not only to prevent the displacement of the member B from its proper rail-gripping position by a rotational movement on an axis substantially parallel to the axis of the rail, but they also provide a locking engagement. Upon reference to the drawings, particularly Figs. 1, 7, and 8, it will be seen that the surface 51 is inclined toward the axis of the rail at substantially the same angle as the wedging surfaces 5—5', that is, the surface 51 is substantially parallel with the surfaces 5—5', but instead of forming the surface 51 precisely parallel to the plane of the wedging surfaces 5—5', there may preferably be a converging of these surfaces toward the tie, as illustrated.

In the initial assemblage the surface 51, at the end 20 of the wedge member, is out of alignment and interferes with the outer surface or end 53 of the lug 50, and when the member B is driven onto the member A toward the right, as viewed in Fig. 4, the lug

50 bites into the surface 51, or the surface 51 cuts into the lug 50, so that a tight engagement is effected, which is adapted to prevent relative movement of the members A and B after they have been driven together to a rail-gripping position. As explained in my prior patents, the surface 51 is inclined in order to prevent an increase in the resistance of the lug 50 to the movement of the member B, as the member B moves transversely of the rail under the influence of the coacting surfaces 5—5', and this inclination of the surface 51 away from the lug 50 corresponds substantially to the rate at which the member B is moved transversely of the rail, thus maintaining a substantially constant relation between the lug 50 and the surface 51 as the rail-gripping action of the members A and B takes place. However, as explained in my prior patent I prefer to make the surface 51 converge slightly with the surfaces 5—5' in the direction of the tie, in order to effect a slight increase in the pressure between the lug 50 and the surface 51, this construction being of particular advantage for the purpose of facilitating a second application of the anchor after it has once been removed from the rail, which is necessary when a new rail is substituted for a defective one. In addition to the locking elements 50 and 51, I may also provide other locking means, such as the narrow rib 60, formed on the end of the member A, opposite the jaw 1—2, which rib is adapted to contact with the inner wall 61 of the member B. The outer surface 62 of the rib 60 slopes outwardly to a slight extent relatively to the plane of the wall 61, thereby effecting a slightly increasing resistance to the movement of the part B as it approaches its rail-gripping position, such rail-gripping movement being provided for the same purpose as explained above in connection with the inclination of the surface 51. A further advantage of the rib 60, in addition to its locking function, is that by means of the rib the member B may be caused to fit closely the end of the reach bar A without the necessity of the utmost precision in manufacture.

From the foregoing description it will be seen that I have provided a rail anchor having inclined coacting wedging surfaces which are adapted to effect a rail-gripping action of the members of the anchor, and which engage each other with an increasing pressure as the members of the anchor are moved relatively to each other into a rail-gripping position. In addition, I have provided other coacting surfaces which engage each other with substantially constant pressure as the members of the anchor are moved relatively to each other, these surfaces being adapted to maintain the two members of the anchor in proper relative rail-engaging position, and to prevent separation of the

members of the anchor under the influence of the expansion of the rail, or under the influence of a movement of traffic in a direction opposite to that in which the rail normally tends to creep. In conjunction with the foregoing features, I may also preferably provide one or more sets of coacting locking elements, which may preferably engage each other with a slightly increasing pressure as the members of the anchor are moved relatively into rail-engaging position, these locking elements serving also to prevent relative separation of the members of the anchor after they have been assembled in normal gripping position.

In the following claims I have referred to the surfaces coacting with constant pressure as being out of alinement; it will be understood that the lack of alinement is such as to cause interference between the surfaces and subsequent pressure of one surface on the other.

While I have shown and described a single embodiment of the invention for purposes of illustration, it will be understood that it may be constructed in various other forms without departing from the spirit thereof as embodied in the appended claims.

What I claim is:

1. A rail anchor comprising a plurality of members having coacting wedging surfaces engaging each other with varying pressure upon relative movement of said members, and having other coacting surfaces engaging each other with substantially constant pressure upon relative movement of said members.

2. A rail anchor comprising a plurality of members having coacting inclined wedging surfaces to draw said members together transversely of said rail as one member is moved relatively to the other longitudinally of said rail, and having other coacting surfaces arranged to engage each other with substantially constant pressure as the relative position of said members is altered.

3. A rail anchor comprising a plurality of members having coacting upwardly extending surfaces to draw said members together transversely of said rail as relative movement is imparted to them longitudinally of said rail, and having other horizontally extending coacting surfaces arranged to engage each other with substantially constant pressure as the relative position of said members is altered.

4. A rail anchor comprising a plurality of members having coacting wedging surfaces engaging each other with varying pressure upon relative movement of said members, and having other coacting surfaces engaging each other with substantially constant pressure upon relative movement of said members, said last mentioned surfaces being normally out of alinement.

5. A rail anchor comprising a plurality of members having coacting inclined wedging surfaces to draw said members together transversely of said rail as one member is moved relatively to the other longitudinally of said rail, and having other coacting surfaces arranged to engage each other with substantially constant pressure as the relative position of said members is altered, said last mentioned surfaces being normally out of alinement.

6. A rail anchor comprising a plurality of members having coacting wedging surfaces engaging each other with varying pressure upon relative movement of said members, other coacting surfaces engaging each other with substantially constant pressure upon relative movement of said members, and other coacting locking parts engaging each other with varying pressure to prevent relative separation of said members.

7. A rail anchor for railway rails, comprising a main member adapted to underlie and engage one edge of a rail base, the other end of said member having an inclined wedging surface, and a second member adapted to engage the other edge of said rail base and said last-mentioned end of said main member, said second member having an inclined wedging surface adapted to coact with said inclined surface on said main member, said main member and said second member having other surfaces adapted to engage each other with substantially constant pressure upon relative movement of said members, one of said members having a part adapted to bear against a tie.

8. A rail anchor for railway rails, comprising a main member adapted to underlie and engage one edge of a rail base, the other end of said member having an inclined surface, and a second member adapted to engage the other edge of said rail base and engage the last mentioned end of said main member by means of a groove along one of its sides, said groove having an inclined wedging surface adapted to coact with said inclined surface on said main member, said main member and said second member being provided with other surfaces adapted to engage each other with substantially constant pressure as said second member is moved with respect to said main member, one of said members having a part adapted to bear against a tie.

9. A rail anchor for railway rails, comprising a main member adapted to underlie and engage one edge of a rail base, the other end of said main member having a shoulder lying in a vertical plane and inclined transversely of said rail, and a second member adapted to embrace said last mentioned end of said main member and to engage the other edge of said rail base, said second member having an inclined wedging surface

- adapted to coact with said inclined shoulder on said main member to draw said members together transversely of said rail, said main member and said second member having other surfaces normally out of alinement and arranged to coact with each other with substantially constant pressure upon relative movement of said members.
10. A rail anchor for railway rails, comprising a member adapted to underlie the base of a rail and to bear against a tie, one end of said member being adapted to hang upon and engage the rail base by means of an upwardly extending part directly engaging one edge of the rail base, and the other end of said member having an upwardly extending shoulder converging in a horizontal plane with the opposite edge of said rail base, said member being provided with a horizontally extending surface on the underside thereof beneath said shoulder, and a second member adapted to overlie the other edge of said rail base and to embrace the last mentioned end of said main member by means of a groove extending along one side thereof, said groove having one part adapted to coact with said upwardly extending shoulder of said main member to effect a transverse gripping of said rail base, said second member being also provided with a horizontally extending surface adapted to engage said horizontally extending surface on said main member, said horizontally extending surfaces being normally out of alinement.
- 35 11. A rail anchor for railway rails, comprising a main member adapted to underlie a rail base and engage one edge thereof, said member projecting beyond the other edge of said rail base and being provided on the projecting end thereof with an inclined wedging surface, and a second member adapted to engage the projecting end of said main member and the other edge of said rail base, said second member having an inclined wedging surface adapted to coact with said inclined wedging surface on said main member, whereby said members will be caused to grip the rail upon relative movement thereof, said members having other coacting surfaces lying in parallel planes and engaging each other with substantially constant pressure over a considerable area when said members are assembled on the rail, one of said members having a part adapted to bear against a tie.
- 50 12. A rail anchor for railway rails, comprising a main member adapted to underlie a rail base and engage one edge thereof, said member projecting beyond the other edge of said rail base and being provided on the projecting end thereof with an inclined wedging surface, and a second member adapted to engage the projecting end of said main member and to engage and overlie the other edge of said rail base, said second member having an inclined wedging surface adapted to coact with said inclined wedging surface on said main member, whereby said members will be caused to grip the rail upon relative movement thereof, said main member having a substantially horizontal surface on the underside of the projecting end thereof lying in a plane substantially parallel to the longitudinal axis of the rail, said second member having a surface lying in a plane substantially parallel to said last-mentioned surface on said main member and adapted to coact therewith with substantially constant pressure when said members are assembled on the rail, one of said members having a part adapted to bear against a tie.
- 65 13. A rail anchor for railway rails, comprising a main member adapted to underlie a rail base and engage one edge thereof, said member projecting beyond the other edge of said rail base and being provided on the projecting end thereof with an inclined wedging surface, and a second member adapted to engage the projecting end of said main member and to engage and overlie the other edge of said rail base, said second member having an inclined wedging surface adapted to coact with said inclined wedging surface on said main member, whereby said members will be caused to grip the rail transversely upon relative movement thereof, said main member having a surface on the underside of the projecting end thereof lying in a plane substantially parallel to the longitudinal axis of the rail, said second member having a surface lying in a plane substantially parallel to said last-mentioned surface on said main member and adapted to coact therewith with substantially constant pressure when said members are assembled on the rail, said last-mentioned surfaces on said main member and said second member being normally out of alinement when said members are brought into initial contact with said main member engaging the underside of said rail base and said second member engaging the upper surface of said other edge of said rail base, whereby when said members are assembled on the rail, a pressure is set up between said coacting interfering surfaces and said second member is maintained in tight contact with said other edge of said rail base, one of said members having a part adapted to bear against a tie.
- 80 14. A rail anchor for railway rails, comprising a main member adapted to underlie a rail base and engage one edge thereof, said member projecting beyond the other edge of said rail base and being provided on the projecting end thereof with a transverse shoulder having an inclined wedging surface, a second member adapted to engage the projecting end of said main member and to

overlie the other edge of said rail base, said second member having an inclined wedging surface adapted to coat with said inclined wedging surface on said shoulder, whereby said members will be caused to grip the rail transversely upon relative movement thereof, said main member having a surface on the underside of the projecting end thereof lying in a plane substantially parallel to the longitudinal axis of the rail, said second member having a surface lying in a plane substantially parallel to said last-mentioned surface on said main member and adapted to coat therewith with substantially constant pressure over a considerable area when said members are assembled on the rail, said horizontal surfaces on said main member and said second member being normally out of alinement when said members are brought into initial contact with said main member engaging the under-surface of said rail base and said second member engaging the upper surface of said other edge of said rail base, whereby when said members are assembled on the rail, a stress is set up in said second member causing it to grip firmly said main member and the adjacent edge of said rail base, and additional coacting elements carried by said main member and said second member for preventing separation of said

members, one of said members having a part adapted to bear against a tie.

15. A rail anchor for railway rails, comprising a main member adapted to underlie a rail base and having an upwardly extending part arranged to engage and hang upon one edge of said rail base, said main member being provided with a part having a substantially horizontal under-surface adjacent the other edge of said rail base, and a second member adapted to hang upon the other edge of said rail base and to engage said main member, said members having coacting wedging surfaces whereby a relative movement of said members will effect a transverse gripping of said rail base, said second member having a surface adapted to extend beneath and coat with said under-surface of said main member, said last mentioned surfaces being out of alinement and interfering when said members are brought together initially with said main member coacting with the under-surface of said rail base and said second member coacting with the upper surface of the rail base, one of 55 said members having a part adapted to bear against a tie.

In testimony whereof, I have subscribed my name.

HENRY G. ELFBORG.
